UNITED STATES PATENT OFFICE.

EDWIN SANFORD PHELPS, OF NEW YORK, N. Y.

RECORDING TIME-LOCK.

1,373,204.

Specification of Letters Patent. Patented Mar. 29, 1921.

Application filed May 28, 1916. Serial No. 100,049.

To all whom it may concern:

Be it known that I, EDWIN S. PHELPS, a citizen of the United States, residing at New York, in the county of New York and State 5 of New York, have invented certain new and useful Improvements in Recording Time-Locks; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

My invention relates to registering time-locks of the type which makes a record of the time, or hour and fraction of an hour, when the lock is operated to lock or unlock 20 the door to which it is attached so that an examination of the record will show the time of opening and closing and the intervening period of time.

The present invention has for its object 25 to reduce the number of parts or gears heretofore employed in operating the record carrying table, disk or plate and to insure greater time accuracy by lessening the friction incidental to constructions heretofore 30 employed and the loss or difference in time resulting therefrom; and to drive the record carrying plate or table by a practically direct connection between said plate or table and the spring drum of the operating clock 35 mechanism as will be hereinafter made to appear; and also to further improve the construction.

To the accomplishment of the foregoing and such other objects as may hereinafter 40 appear the invention consists in the features hereinafter particularly described and then sought to be clearly defined by the claims, reference being had to the accompanying drawings forming part hereof, and in 45 which:

Figure 1 is a front elevation of a registering lock embodying the invention, partly in section on line 1—1 of Fig. 2, and with same parts broken away;

Fig. 2 is a vertical section on the line 2—2 of Fig. 1;

Fig. 3 is a side view, partly in section, of the record carrying table operating parts;

Fig. 4 is a detail, looking at the front of 55 the plate supporting the snail mechanism;

Fig. 5 is a plan view of Fig. 4;

Fig. 6 is a side view looking at the opposite side of the plate from Fig. 4;

Fig. 7 is a section on the line 7—7 of 60 Fig. 4;

Fig. 8 is a perspective of the lever which lifts the plate carrying the snail;

Fig. 9 is a perspective of the slideable plate which carries the snail and its operating parts; 65

Fig. 10 is a perspective of the stylus; and

Fig. 11 is a face view of the record-receiving dial.

In the drawings the numeral 1 designates a portion of a door having attached thereto 70 a lock-case 2 containing a bolt 2^a actuated from the inside by a key applied to the lock 3 or from the outside by a key actuating the lock tumbler 4 whose stem carries studs 5 engaging the rack 6. The case also contains the lever 7 actuated in the movement 75 of the bolt for lifting the plate 8 guided by the plates 8^a and 8^b and normally pressed downward by spring 8^c, and which carries the pinions 9 and 10 and toothed wheel 11 80 and its snail 12 which coöperate with the marker or stylus 13 and its snail actuated arm 14, held to place by the spring 14^a as heretofore in a well known construction 85 of this type of lock, the casing also being provided with a hinged lower lid 15 and known form of locking members 16 and 17, and further provided with an upper hinged lid or cover 18 provided with an approved type of lock 19, or one having a rotatable 90 locking tongue 20 the details of which are not illustrated because not claimed herein. The parts thus generally referred to may be of the general construction heretofore employed and therefore need no further description. 95

In locks of this type of my make the plate or table carrying the record-receiving dial has been actuated by a pinion meshing with a toothed wheel from which rotation was 100 transmitted to the record table or plate, the pinion being carried by a shaft the inner end of which carried a pinion meshing with the toothed gear of the spring driving drum of the clock mechanism. If the pinion at 105 the outer end of the shaft mentioned was accurately adjusted good results in the accuracy of time was possible but if not so adjusted there was likely to be more or less loss of time recorded in the course of twenty-four hours, or in a longer or shorter period of time, and there was also considerable 110

friction between the parts which it is desirable to overcome with the view of insuring greater accuracy in keeping or recording of time. With the view of removing the objections noted I have devised the following construction: The train of clock mechanism will be set somewhat off center, and the shaft or spindle 21 which will carry the recording dial table or disk 30 is set practically dead center and above the spring drum 23 of the clock mechanism and has a gear or toothed wheel 24 which meshes with the gear 25 of the spring drum so that the dial carrying table will be revolved directly from the spring drum through the shaft 21. The toothed wheel 24 is frictionally held to the shaft 21 by a collar 26 held fixedly to the shaft at one side of the gear and by a coiled spring 27 bearing at one end against a loose washer 28 bearing against the wheel and at the end bearing against a collar 29 fixedly held to the shaft. This permits the shaft 21 to be turned against the friction exerted by the coiled spring when it is desired to adjust the table carrying the record-receiving dial in setting the dial for the time of day to which the record-receiving dial is set or adjusted for its work, the toothed wheel 24 at such time being held against rotation by reason of meshing with the toothed wheel 25 of the spring drum.

On the outer end of the spindle or shaft 21 is mounted the table or disk 30 which carries the record-receiving dial 31 and also the attached pinion 32, the table and the pinion being attached to the spindle so as to turn therewith by making a portion of the spindle angular in cross section as shown at 33, or otherwise, and prevented from moving lengthwise thereon by means of a beaded screw 34 entering the end of the spindle and its head bearing against the end of a tubular extension or sleeve 35 projecting centrally from the face of the table 30. The record-receiving dial 31 is held to the table or disk 30 by studs 36 on the table projecting through corresponding openings 37 in the record-receiving dial and by spring fingers 38 carried by a thumb nut 39 screwed onto the threaded extension or sleeve 35. The pinion 32 of the table 30 meshes with the pinion 9 so as to rotate it and the connected pinion 10 for rotating the toothed snail wheel 11 with the teeth of which it meshes. From the foregoing it will be appreciated that the record carrying dial is carried by a spindle actuated through a single gear directly from the spring drum, and that said shaft is set practically dead center and above the spring drum, which results in reducing the number of gears for transmitting motion to the record carrying dial and also the friction incident to the parts dispensed with, and insures a more accurate time keeping. It also provides for the pinions through

which motion is transmitted to the snail carrying wheel having motion transmitted thereto directly from the shaft which carries and drives the record carrying dial as well as providing for an easier and simpler placing in position and removal of the record carrying dial and associated pinion through which movement is transmitted to the pinion that transmits movement to the snail carrying wheel.

The record receiving dial is made as usual of a sensitized paper preferably divided radially into subdivisions of hours and fractions of hours for ready reading although such subdivisions are not absolutely essential. The stylus makes an arcuate trace on the record receiving dial during the period that the bolt is in its locked as well as unlocked positions preferably in one arc for one position and in a different arc for another position, and also radial traces in throwing the bolt from one position to another; as is the case in some registering locks of this type.

At the point where the stylus makes its mark on the record receiving dial there is provided a backing-plate 40 for the record-paper which plate may be supported from the plate 41 to which other parts of the mechanism are attached.

I have illustrated and described the preferred construction of the parts embodying the invention but changes can be made therein and essential features of the invention retained.

Having described my invention and set forth its merits what I claim is:—

1. In a time-recording lock including clock-mechanism, its motor, and a record-receiving member; a table for the record-receiving member, and a rotatable spindle carrying at one end the table and geared to the motor of the clock-mechanism independently of the train of clock gearing.

2. In a time-recording lock including clock-mechanism, its motor, and a record-receiving member; a table for the record-receiving member, a rotatable spindle carrying at one end the table and at the other end geared to the motor of the clock-mechanism, the spindle and gear through which it derives motion being frictionally connected with each other.

3. In a time-recording lock including clock-mechanism, its motor, and a record-receiving member; a table for the record-receiving member, a rotatable spindle carrying the table, a gear mounted on the spindle and operatively connected with the motor, the spindle being capable of movement independently of the gear, and a spring effecting a frictional connection between the spindle and gear for joint rotation.

4. In a time-recording lock including clock-mechanism, its motor, and a record-receiving member; a stylus, a gear and snail

for moving the stylus; a rotatable spindle geared to the motor, a table mounted on the spindle to carry the record-receiving member, and a pinion mounted on the spindle in 5 position to mesh with another pinion through which movement is transmitted to the snail operating gear, the movement of the spindle in either of two directions shifting the snail

and stylus relatively to the record-receiving member.

In testimony whereof I affix my signature in presence of two witnesses.

EDWIN SANFORD PHELPS.
